UNITED STATES PATENT OFFICE.

EULAH MYRTLE SUMMERS, OF BIRMINGHAM, ALABAMA.

DESIGN FOR A BIFURCATED NETHER GARMENT FOR CHILDREN.

Application filed June 6, 1922. Serial No. 2,550. Term of patent 7 years.

To all whom it may concern:

Be it known that I, EULAH MYRTLE SUMMERS, a citizen of the United States, residing at Birmingham, in the county of Jefferson and State of Alabama, have invented a new, original, and ornamental Design for a Bifurcated Nether Garment for Children, of which the following is a specification, reference being had to the accompanying drawing, forming part thereof.

The figure is a front view of a bifurcated nether garment for children, showing my new design.

I claim:

The ornamental design for a bifurcated nether garment for children, substantially as shown.

EULAH MYRTLE SUMMERS.
